UNITED STATES PATENT OFFICE.

SILAS H. RANDALL, OF WYOMING, OHIO.

DESIGN FOR A BRACKET.

SPECIFICATION forming part of Design No. 23,223, dated April 24, 1894.

Application filed February 26, 1894. Serial No. 501,610. Term of patent 7 years.

To all whom it may concern:

Be it known that I, SILAS H. RANDALL, a citizen of the United States, residing at Wyoming, in the county of Hamilton and State 5 of Ohio, have invented and produced a new and original Design for a Bracket; and I do hereby declare the following to be a full, clear, and exact description of the same, reference being had to the accompanying drawing, forming a part thereof.

My design is for a bracket, and the leading features thereof are the elements A, B, C,

provided with the upward projections D, D', and downward projections E, E', as shown in the drawing.

I claim as my invention—

The design for a bracket, as herein shown, and described.

In testimony whereof I affix my signature in presence of two witnesses.

SILAS H. RANDALL.

Witnesses:

JAMES H. LAYMAN,
ARTHUR MOORE.
